(57) CLAIM

The ornamental design of a probe bender for an electrosurgical tool, as shown and described.

DESCRIPTION

FIG. 1 is a perspective view of a probe bender for an electrosurgical tool showing my new design;

FIG. 2 is a top plan view thereof;

FIG. 3 is a bottom plan view thereof;

FIG. 4 is a right side view thereof;

FIG. 5 is a left side view thereof;

FIG. 6 is a front view thereof;

FIG. 7 is a rear view thereof; and,

FIG. 8 is a perspective view thereof.

The broken line showing of the incremental marks on the probe bender in FIGS. 1, 4 and 5, and of the electrosurgical tool in FIG. 8 are for illustrative purposes only and forms no part of the claimed design.
